CLAIM

The ornamental design for a garden storage box, as shown and described.

DESCRIPTION

FIG. 1 is a front, right and top perspective view of a garden storage box showing my new design;

FIG. 2 is a front side view thereof;

FIG. 3 is a rear view thereof;

FIG. 4 is a right side top view thereof;

FIG. 5 is a top view thereof;

FIG. 6 is a bottom view thereof; and,

FIG. 7 is a rear, left and bottom view thereof.

The surface shading on the surfaces on the garden storage box represents a wood grain appearance.

The broken lines form no part of the claimed design.
